SHIPPING DRUM

Oscar J. van Leer, Chicago, Ill., and Christian Ragettli, Zurich, Switzerland, assignors, by mesne assignments, to Inland Steel Container Company, Chicago, Ill., a corporation of Illinois

Filed Dec. 1, 1960, Ser. No. 73,070

7 Claims. (Cl. 220—71)

The present invention relates to shipping drums, and, more particularly, to a means for reinforcing the end of the drum against harmonic oscillation.

During recent years the demand for relatively light-weight shipping drums capable of withstanding the rigors of transportation has been increasing. Such drums, in the standard fifty-five gallon size, are generally filled with a liquid material and transported via truck and/or railroad cars to either a point of consumption or storage.

Along with increased demand for such drums has been the desire to reduce the costs of manufacture and transportation of the drums. In an effort to overcome the weight and cost problems, manufacturers have followed a trend to thinner and lighter metal.

Shippers have been continuously plagued by drum failures resulting from metal fatigue, particularly in that region where the end member of the drum meets the side walls known as the "knuckle radius." Such metal fatigue, and consequent drum failure, has been found to result from the localized bending accompanying the harmonic oscillations which are reduced in the end member of a filled drum during transport. The problem of "drum-head harmonic oscillation" has become increasingly vexing with the use of thinner and lighter metal stock.

The fatigue and resulting fracture becomes a particularly serious problem when transporting hazardous material such as gasoline, corrosive liquid chemicals, and the like. Efforts have been made to reinforce the drum ends, for example, by going to special contours or by using a heavier gauge material. However, special contours have not been particularly satisfactory, and any appreciable increase in the thickness of the metal adds to the cost and dead weight.

Accordingly, it is an object of this invention to provide a drum having a reinforced flat end member which is stronger than the end members conventionally employed. It is a more specific object to provide reinforcing means capable of minimizing "drum-head" harmonic oscillations during transportation of the drum. It is a related object to provide a novel reinforcing element capable of minimizing harmonic oscillation and reducing vibrational flexure of a drum end member, which flexure results in metal fatigue.

It is another object to provide an end member which facilitates stacking the drums in a straight stack and which makes it unnecessary for care to be exercised in alining the drums with one another seam-to-seam. Cumulative "cocking" error is thereby minimized, neat stacking is assured and risk of toppling is avoided.

It is a further object to provide a novel reinforcing means for use with shipping drum end members and which at the same time serves to distribute sharply concentrated forces over a wide area, thus reducing the unit stress to a level below that which will cause severe denting or puncturing. It is, therefore, an object to provide a drum having a bottom capable of resisting puncturing when the drums are stacked on rough or uneven storage spaces, for example, in primitive oil producing areas.

It is another object to provide an improved shipping drum end member and reinforcing means therefor so as to allow the drum to be constructed from a lighter gauge

2

metal than would otherwise be used, with a consequent saving in both cost and dead weight.

These and other objects and advantages of this invention will become apparent upon reading the attached detailed description and upon reference to the drawings in which:

FIGURE 1 is a perspective view of an assembled shipping drum embodying the invention;

FIG. 2 is an enlarged cross section through one of the reinforcing cup members employed in accordance with the invention;

FIG. 3 is a section taken along the line 3—3 in FIG. 1 to bring out the height relationships according to the preferred embodiment of this invention;

FIG. 4 is an end view of a shipping drum disclosing a modified form of a reinforcing member; and

FIG. 5 is a section taken along the line 5—5 in FIG. 4.

While this invention has been described in connection with a preferred embodiment, it will be understood that it is not intended to be limited to this specific embodiment, but rather to cover such equivalent and alternative construction as may be included within the spirit and scope of the appended claims.

Referring to the drawing there is illustrated in FIG. 1 a shipping drum 10 having a cylindrical wall or body 11 which includes two or more spaced beads 12 to strengthen the drum and to facilitate rolling it. Secured to the bottom of the drum is an end member 15 which is joined to the drum wall by a curled seam or chime 16. Concentration of the metal at the seam reinforces the drum as a whole and permits it to be tipped or rolled on edge. Moreover, the seam 16 serves to transmit edgewise force to the drum wall when the drums are stacked in alinement, seam-to-seam.

To form the seam the end member 15 is in the form of a flat disk 18 having an upstanding annular bead 20 (FIG. 3) about its periphery and defining an annular channel 21 which engages one end of the cylindrical drum wall 11. It will be understood that after the drum wall 11 is seated in place within the channel 21, and as a subsequent manufacturing step, the two members are curled together in overlapping relation to form the end seam 16. The flat central disk 18 is recessed with respect to the seam by a predetermined depth as indicated at "d" in FIG. 3.

It will be understood that when a shipping drum as hereinbefore described is being transported in the filled condition, the bobbing motion of the transporting vehicle is transmitted to the liquid within the drum. The liquid and resilient end member of the drum together form a resonant, oscillating system with the result that destructive harmonic oscillation is built up in the drum end member, even though the initiating vibration is of low amplitude. When the oscillation continues over a period of days the result is fatigue and fracture, often with leakage of the entire contents. The time required to produce this destructive effect in a shipping drum is dependent on various factors such as the period and amplitude of the initiating vibration, the nature and hardness of the metal as well as its thickness, and the density of the liquid being transported. Some understanding of the forces involved may be gained from the fact that a shipping drum filled with water weighs approximately 500 pounds, the water being incompressible and confined so that its full effect is exerted on the thin bottom member.

In accordance with one of the important aspects of this invention, extensive reinforcing elements having a height equal to that of the bead are rigidly secured to the bottom surface of the drum for supporting the same and arranged in face-to-face contact over a substantial portion of the surface for inhibiting flexional vibration. In the preferred embodiment of this invention, three such reinforce-

ing elements of channel cross section, here in the form of cups 31, 32 and 33, have been employed and are affixed to the end member in a two dimensional, triangular pattern, as illustrated in FIG. 1. Of course, while three such cups have been shown as affixed to the end member 15 in a triangular configuration, it will be understood that the particular number of reinforcing elements employed and the particular pattern in which they are arrayed may vary without departing from the invention. Moreover, the reinforcing elements may take other forms as illustrated in FIG. 4 and to be discussed at a later point. While we have disclosed particular forms of reinforcing members and particular configurations, it will be understood that the forms and configurations may be varied while still falling within the true scope and spirit of this invention.

Referring to FIG. 2, and in accordance with the preferred embodiment of this invention, a typical cup 31 has been illustrated. It will be noted that the cup 31 is of channel-like cross section having a base 35, and an upstanding wall 36 which terminates in an outwardly extending flange 37. The height of the cup indicated at "d" is preferably constant over the entire area thereof and preferably equal to the height of the upstanding bead 20. Thus, the bottom portion 35 of the cup and the base of the bead 16 define a substantially flush supporting surface for the drum. The cup flanges 37, which extend over a substantial area of the flat disk portion 18 of the end member 15 in face-to-face contact therewith, are spot welded at spaced intervals to the bottom surface 19 thereof as, for example, indicated at 38 in FIG. 3.

While this invention has been described in connection with a shipping drum having reinforcing elements secured to only the bottom end member thereof, it will be understood that the reinforcing elements may also be secured to the top end member in a similar manner, thus allowing the drums to be stacked one upon another either upright or in inverted position.

In effect, the reinforcing cups form a plurality of box-like protrusions which are rigidly secured to the bottom surface 19 of the end member. Analysis shows that the reinforcing elements serve several distinct functions. First of all, the elements 31-33 serve as supporting pedestals so that the weight of the contents is not diaphragm supported but rather transmitted directly to the underlying surface. But even when the reinforcing members are not in actual contact with a supporting surface the arrangement is beneficial since the extensive face-to-face contact between the end member and the reinforcing elements, and the rigid nature of the latter, prevent the end member from acting as a vibrating diaphragm. Not only is the end member rigidified but the period of natural vibration is changed so that it is no longer resonant under transport conditions.

Moreover, shipping drums employing reinforcing elements of channel-shaped cross section may be stacked upon one another to substantial heights without subjecting the bottom of the lowermost drum to localized puncturing stress resulting from irregularities and projections on the supporting surface. Such localized pressures can cause denting, weakening of the metal, or actual puncturing when exerted against the bottom of a drum that is not equipped with reinforcing means of the type disclosed in this invention. However, by use of this invention, the bottom portions 35 of the cups in effect serve as a "double bottom" and any concentrated pressure applied to one of the cups is distributed over a substantial area of the end member. Finally, the bottom portions 35 of the cups and the end seam 16 of the drum provide a substantially flush supporting surface which will enable the drums to be stacked one upon another without having to align the drums seam-to-seam. Even when the drums are slightly offset from one another, the cups tend to keep the drums "square" and prevent them from "cocking." Where the

drums are stacked in a plurality of tiers the cocking error tends to be cumulative and thus creates a toppling hazard. With the use of the present invention, the danger of toppling is minimized and neat and safe stacks are provided.

While the preferred embodiment of this invention contemplates the use of a plurality of flanged hollow cups, it will be understood that other forms of reinforcing members may be used. For example, a single large cup may be used as set forth in FIGS. 4 and 5. Here the cup, indicated at 40, is axially centered with respect to the drum bottom 15a and has a diameter which is approximately one-third that of the drum itself. Encircling the cup is a flange 41 having a series of spot welds 42 to the drum bottom. Preferably the cup is dished inwardly at the center for face-to-face contact over a limited area 43. This adds to the rigidity providing support about a circle 44 and enabling thinner metal to be used than would otherwise be possible. The advantages of the reinforcing member 40 are substantially the same as is the earlier embodiment. Where the drums are stacked, and assuming that the disclosed reinforcement is used top and bottom, direct contact between the opposed reinforcing members is assured. Even though the drums may not be perfectly centered, the circles 44 are certain to intersect in direct supporting engagement. With regard to the bottom drum in the stack, this need not be seated on a perfectly flat supporting surface to get the desired supporting effect; if only a portion of the circle 44 touches that is enough to prevent harmonic vibration. If, as may occur under some circumstances, no part of the reinforcing member is supported, the member still acts to rigidify the bottom to dampen any vibrations therein and thereby to effectively inhibit any tendency toward oscillation. Thus, fatigue, and resulting rupture, are prevented under all possible conditions of use.

While the invention has been described in connection with preferred reinforcing elements having a height substantially equal to the height of the upstanding bead 20, thereby providing a substantially flush supporting surface, it will be understood that the supporting elements could have a slightly lesser height without departing from certain aspects of the invention.

Moreover, not only does the use of reinforcing elements secured to a shipping drum end member serve to inhibit harmonic oscillations, to facilitate stacking and to prevent puncture and/or denting, but, as a net effect, it enables shipping drums to be constructed of a thinner gauge metal with a substantial reduction in the initial expense of manufacture and a further reduction in the amount of dead weight that must be shipped. With the use of reinforcing elements of this nature, metal gauges as thin as 24-gauge in the case of a fifty-five gallon drum become practical.

55 In our copending application Serial No. 807,517 filed August 20, 1959, now abandoned, a novel method of forming reinforcing cups from scrap and applying them to the end member of a shipping drum has been disclosed. Reinforcing elements used in the first embodiment of the present invention may ideally be formed using the method disclosed in the aforesaid copending application.

60 It will be understood that our novel reinforcing means is not restricted to use with a perfectly flat end member, but rather will provide similar oscillation inhibiting characteristics, and is equally applicable when used with shipping drums having generally flat, i.e., slightly concave or convex end members, and it is this latter meaning which is intended in the following claims.

We claim as our invention:

70 1. A reinforcing member for use with shipping drums having a flat end member that is subjected to drum-head harmonic oscillations during transport, said reinforcing member comprising an extensive flanged support element having a channel-shaped cross section, said support element having its flanges rigidly secured to said flat end

member in face-to-face contact over a substantial area of the latter so that said drum-head harmonic oscillations will be damped.

2. In combination with a shipping drum having a substantially flat end member that is subjected to drum-head harmonic oscillations during transport, reinforcing means comprising at least one extensive flanged support element of channel-shaped cross section, said support element rigidly secured to said end member over a substantial area of the latter and having its flanges in face-to-face contact therewith so that said end member will be maintained in a substantially unflexed, relatively flat condition.

3. In a shipping drum, a drum wall, an end member in the form of a disk having an upstanding bead portion at its periphery defining a channel for engaging the drum wall and the upstanding bead portion further surrounding and defining a flat central portion, flanged reinforcing means rigidly secured to the flat central portion of said disk and overlying a substantial portion of the area thereof with the flange in face-to-face contact with the disk so that harmonic drum-head oscillations in said end member are substantially minimized during transport and so that the flat central portion of said disk is maintained in a substantially unflexed condition.

4. In a shipping drum, a drum wall, an end member in the form of a disk having an upstanding bead portion at its periphery defining a channel for engaging the drum wall and with the upstanding bead portion further surrounding and defining a flat central portion, flanged reinforcing means rigidly secured in face-to-face contact to the flat central portion of said disk over a substantial area of the latter, said reinforcing means having a height substantially equal to the height of said upstanding bead portion so that said upstanding bead portion and said reinforcing means define a substantially flush supporting surface and the flat central portion of said disk is restrained from harmonic oscillations during transport.

5. In a shipping drum, a drum wall, an end member in the form of a disk having an upstanding bead portion at its periphery defining a channel for engaging the drum wall and the upstanding bead portion further surrounding and defining a flat central portion, reinforcing means secured to the flat central portion of said disk for minimizing harmonic drum head oscillations, said reinforcing means comprising a plurality of flanged support elements spaced from one another and having a substantially channel-shaped cross section, said support elements having their flanges welded to the flat central portion of said disk to form a plurality of box-like protrusions on the

latter, each of said support elements defining with said disk a double bottom for protecting said end member against deformation when the drum is placed on an irregular surface.

5 6. In a shipping drum, a drum wall, an end member in the form of a disk having an upstanding bead portion at its periphery defining a channel for engaging the drum wall and the upstanding bead portion further surrounding and defining a flat central portion, reinforcing means secured to the flat central portion of said disk comprising at least one hollow support element having a substantially channel-shaped cross section and having flanges in face-to-face contact with and welded to a substantial portion of the area of the disk for minimizing harmonic

10 15 drum-head oscillations, said support element further having a height substantially equal to the height of the said upstanding bead portion so that said upstanding bead portion and said support element define a substantially flush supporting surface for protecting said end member against deformation when the drum is placed on an irregular surface.

15 20 7. In a shipping drum, a drum wall, an end member in the form of a disk having an upstanding bead portion at its periphery defining a channel for engaging the drum wall and the upstanding bead portion further surrounding and defining a flat central portion, oscillation inhibiting means secured to the flat central portion of said disk for minimizing harmonic drum-head oscillations, said inhibiting means comprising a plurality of flanged metal

25 30 35 cups secured at spaced points in a two dimensional pattern on said central portion and covering a substantial portion of the area of the latter, said cups having their flanges in face-to-face contact with the metal of said disk and welded to the disk and said cups substantially equal to the height of the upstanding bead portion so as to form with said bead portion a substantially flush supporting surface for protecting the end member against deformation when the drum is supported on an irregular

40 surface.
